UNITED STATES PATENT OFFICE.

CHRISTIAN SELISNIK, OF CLEVELAND, OHIO.

DESIGN FOR A FLAG-HOLDER.

59,875.

Specification for Design.

Patented Nov. 29, 1921.

Application filed June 20, 1921. Serial No. 479,142. Term of patent 7 years.

To all whom it may concern:

Be it known that I, CHRISTIAN SELISNIK, a citizen of Jugoslavia, residing at Cleveland, in the county of Cuyahoga and State of Ohio, have invented a new, original, and ornamental Design for a Flag-Holder, of which the following is a specification, reference being had to the accompanying drawing, forming part thereof.

The figure is a view in perspective of a flag holder, showing my new design.

I claim:

The ornamental design for a flag holder, as shown.

CHRISTIAN SELISNIK.
